United States Patent

Des. 239,000
Patented Mar. 2, 1976

239,000

RIVET GUN

Gabriel M. La Pointe, Worcester, Mass., assignor to
Parker Manufacturing Company, Worcester, Mass.

Filed June 21, 1974, Ser. No. 481,495

Term of patent 14 years

Int. Cl. D8—05

U.S. Cl. D8—51

FIG. 1

FIG. 2

FIG. 4

FIG. 3

FIG. 5

FIG. 1 is a perspective view of a rivet gun showing my new design,

FIG. 2 is a front elevational view of the gun taken from the right side of FIG. 2,

FIG. 3 is a side elevational view of the gun,

FIG. 4 is a top view of the gun, and

FIG. 5 is another side elevational view of the gun taken from the left side of FIG. 2.

The rear elevational view of the gun is substantially the mirror image of FIG. 2.

I claim:

The ornamental design for a rivet gun, as shown and described.
